2 SHEETS—SHEET 2.

UNITED STATES PATENT OFFICE.

WALFRID S. EKLUND, OF DONNER, LOUISIANA.

MEANS FOR STEERING BOATS.

1,257,825.

Specification of Letters Patent. Patented Feb. 26, 1918.

Application filed May 29, 1917. Serial No. 171,721.

To all whom it may concern:

Be it known that I, WALFRID S. EKLUND, a citizen of the United States, residing at Donner, in the parish of Terrebonne and 5 State of Louisiana, have invented certain new and useful Improvements in Means for Steering Boats; and I do hereby declare the following to be a full, clear, and exact description of the invention, such as will enable others skilled in the art to which it 10 pertains to make and use the same.

This invention relates to means for steering boats and has for one of its objects the provision of a device of this character, 15 which may be readily applied to the bow of a boat, and which will coöperate with the ordinary rudder on the stern thereof to permit of turning the boat in a small space and whereby the boat may be quickly turned 20 from a straight course or run in a zigzag path providing means especially adapted for combating submarine boats.

Another object of this invention is to provide an auxiliary rudder mounted on the 25 bow of the boat and adapted to be actuated by a fluid pressure means and which cooperates with the ordinary rudder on the stern in steering the boat.

A further object of this invention is to 30 provide a pair of cylinders having pistons therein, which are connected to the auxiliary rudder and are alternately actuated by fluid pressure to turn or move said rudder in either direction.

A still further object of this invention is 35 the provision of means for steering boats of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a plan view partly in section

of a means for steering boats constructed in accordance with my invention,

Fig. 2 is a side elevation of the same,

55

Fig. 3 is a plan view of an indicator,

Fig. 4 is a side elevation of a four-way valve applied for controlling the fluid pressure to the cylinders of the device.

Referring in detail to the drawings, the 60 numeral 1 indicates a frame, which may be of any desired shape or configuration, but preferably of the shape as shown in Fig. 1 having a reduced end 2 and an enlarged end 3. The reduced end 2 of the frame 1 is 65 bifurcated to form a pair of relatively spaced arms 4, in which are formed bearing openings to receive the post 5 of a rudder 6, the post 5 being held within the bearing openings of the bifurcated arms 4 of 70 the frame by a nut 7 or other suitable fastener. The frame 1 is secured to the bow of a boat 8 as shown in Fig. 1, so that the post 5 is disposed vertically and is forward 75 of the stem.

The enlarged end 3 of the frame 1 is bifurcated to receive a double segmental drum 9, which is journaled on a shaft 10 carried by the enlarged end 3 of the frame. A driven drum 11 is secured to the post 5 80 of the rudder 6 between the bifurcated arms 4 of the reduced end 2 of the frame and has its periphery provided with grooves to receive several convolutions of a cable 12, which cable passes about the segmental 85 drum 9 as clearly shown in Fig. 2 and has its ends connected to eye-bolts 13 that are adjustably connected to an arm 14 formed upon the segmental drum 9, as clearly shown at 15. A pair of relatively spaced 90 ears 16 are carried by the driven drum 11 and have connected thereto, a clamping member 17 by bolts 18, which engages and forces the convolutions of the cable 12 into a groove 19 in the driven drum 11, thus preventing the cable 12 from slipping upon said driven drum.

The frame 1 is provided with a downwardly offset portion 20 having secured therein, cylinders 21 and 22 by fasteners 23. 100 Pistons 24 are slidably mounted within the cylinders and are connected to oppositely disposed arms 25 of the segmental drum 9 as shown at 26 by connecting rods 27. The

pistons are adapted to be alternately actuated within the cylinders by fluid pressure means, which will be hereinafter more fully described for moving or turning the segmental drum 9 in either direction, which will cause the driven drum 11 to turn in either direction, moving the rudder 6 in a corresponding direction to facilitate the steering of the boat 8 by the bow and which is adapted to coöperate with an ordinary rudder, (not shown) placed upon the stern of the boat, whereby a steering mechanism is provided for the boat, which will cause said boat to be very sensitive to the steering power thereof.

The rudder 6 is provided with the usual reinforcing plates 29, which are apertured to receive the looped portions 30 of fastening members 31 that are secured to the bow 20 of the boat by fasteners 32. The looped portions 30 extend around the stem 5 within the reinforcing members 29 as clearly shown in Fig. 2.

A four-way valve 33 consists of a body 25 portion having ports 34, 35, 36 and 37. An ordinary plug 38 is located within the body of the valve 33 and has connected to its upper end, an operating handle 39. The plug 38 is held in tight engagement with the 30 walls of the body of the valve 33 by an ordinary spring 40. The plug 38 is provided with passages 41 and 42. A pipe 43 is connected to the port 37 and to the interior of the cylinders 21. A similar pipe 35 44 is connected to the port 35 and to the interior of the cylinder 22. A supply pipe 45 is connected to the port 34 and to an ordinary hydraulic pump, (not shown), for forcing fluid pressure into the valve 33. 40 An outlet pipe 46 is connected to the port 36 and to a reservoir, (not shown), that is associated with the hydraulic pump whereby the used fluid pressure may be again forced through the valve.

45 In operation, when it is desired to steer the boat to the left, the handle 39 is turned so that the passage 41 communicates with the ports 34 and 35, permitting the fluid pressure to pass through said ports into the 50 pipe 44 and then into the cylinder 22 forcing the pistons therein outwardly, turning the segmental drum 9, which through the cable 12, turns the driven drum 11 secured to the stem 5 of the rudder, turning the 55 rudder to the left, thus turning or steering the boat to the left.

When it is desired to steer or turn the boat to the right, the handle 39 is moved in an opposite direction from the direction hereto described, causing the passage 60 41 to communicate with the ports 34 and 37, which permits the fluid pressure to enter the pipe 43 and to the cylinder 21 and forces the piston therein outwardly which

turns the segmental drum 9 in an opposite 65 direction, moving the driven drum 1 in a corresponding direction from the cable 12, which moves the rudder 6 to the right, thus steering the boat to the right. When the passage 41 communicates with the ports 34 and 35, the passage 42 communicates with the ports 35 and 36, permitting the fluid contained within the cylinder 22 to return to the valve by way of the pipe 44 and to the reservoir, (not shown) by the pipe 46. 70 75 This operation also applies to the cylinders 21 when fluid pressure is being supplied to the cylinder 22.

The valve 33 is mounted within the pilot 80 house of the boat along with ordinary steering mechanism now employed for operating the rudder upon the stern of the boat. A plate 47 having a scale thereon is secured within the pilot house along with the valve 33 and has mounted thereon, an indicating 85 arrow 48 to which is connected upon one side thereof, a coiled spring 49. The spring 49 has its other end connected to the plate 47 as shown at 50. A cable 51 is connected to the indicating arrow 48 and to the arm 90 14, whereby a person operating the device may readily determine by the indicating hand upon the scale just what position the rudder 6 is occupying.

While I have shown and described the 95 preferred embodiment of my invention, it will be understood that minor changes in construction, combination and arrangement of parts may be made without departing from the spirit and scope of the invention 100 as claimed.

Having thus described my invention, what I claim is:

1. A means for steering a boat comprising a frame secured to the bow of the boat, 105 a rudder carried by said frame, a driven drum secured to said rudder, a drive drum journaled to said frame, means for connecting the drums, and hydraulic means for operating the drive drum for steering the 110 rudder in either direction.

2. A means for steering a boat comprising a frame secured to the bow of the boat, a rudder carried by said frame, a drum carried by said rudder, a double segmental 115 drum carried by said frame, a cable connecting said drums, means for adjusting the tension of said cable, means for turning the segmental drum in either direction to turn the rudder in a corresponding direction.

3. A means for steering a boat comprising a frame secured to the bow of the boat, a rudder journaled to said frame, a drive drum journaled to said frame, means for 125 connecting the drum to the rudder, cylinders carried by said frame, pistons in said cylinders and connected to the drum,

and means for admitting fluid pressure to the cylinders for turning the drum in either direction to move the rudder in a corresponding direction.

- 5 4. A means for steering a boat comprising a frame secured to the bow of the boat, a rudder carried by said frame, a drum carried by said rudder, a double segmental drum carried by the frame, a cable connecting said drums, means for securing the cable upon the first mentioned drum, and hydraulic means for turning the double segmental drum in either direction to turn the rudder in a corresponding direction.
- 10 5. A means for steering a boat comprising a frame secured to the bow of the boat, a rudder carried by said frame, a drum journaled to said frame, means for connecting the drum to the rudder, cylinders carried by said frame, pistons in said cylinders
- 15
- 20

and connected to the drum, pipes connected to said cylinders, a four-way valve connected to said pipes, and adapted to admit an exhaust fluid pressure to the cylinders for actuating the rudder.

25

6. A steering device comprising a frame secured to the bow of a boat, a drum journaled to each end of said frame, a rudder connected to one of said drums, means connecting the drums together, and hydraulic means carried by the frame and operatively connected with one of the drums to turn the rudder.

In testimony whereof I affix my signature in presence of two witnesses.

WALFRID S. EKLUND.
